US00D528986S

(12) **United States Design Patent** (10) Patent No.: **US D528,986 S**
Su (45) Date of Patent: **** Sep. 26, 2006**

(54) **MEMORY CARD CONNECTOR**

(75) Inventor: **Yu-Hung Su**, Tu-Cheng (TW)

(73) Assignee: **Cheng Uei Precision INdustry Co., Ltd.**, Taipei Hsien (TW)

(**) Term: **14 Years**

(21) Appl. No.: **29/245,617**

(22) Filed: **Dec. 27, 2005**

(51) LOC (8) Cl. **13-03**

(52) U.S. Cl. **D13/147**

(58) Field of Classification Search **D13/133, D13/146-147, 149, 154, 184; D14/432-436, D14/438; 439/64, 79, 159-160, 326, 492, 439/496, 607-610, 630-631, 862**

See application file for complete search history.
